Primary Examiner — Katrina N Gonzalez

(57) **CLAIM**

The ornamental design for a water drinking device for animals, as shown and described.

DESCRIPTION

FIG. 1 is a front elevational view of a water drinking device for animals showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front, and right side perspective view thereof;

FIG. 8 is a bottom, rear and left side perspective view thereof; and,

FIG. 9 is an enlarged detail view of area 9 shown in FIG. 7. The broken lines in the drawings illustrate portions of the water drinking device for animals FIGS. 7 and 9 show broken lines that represent the boundaries and indicators of the enlarged detail view. The broken lines form no part of the claimed design.

1 Claim, 9 Drawing Sheets
